EMPLACEMENT FORMER

Fred Gerriets, Alexandria, Va.

Application June 3, 1939, Serial No. 277,305

7 Claims. (Cl. 72—0.5)

This invention relates to the formation in concrete masonry, tile, wood and other structures, of recesses or fitting emplacements in relation to elements to be held in the concrete or other floors, walls, and other structures. In the present instance the invention is adapted to embody means for facilitating the installation of water closets or other equipment in bathrooms, public toilets and other places. It is particularly de-

10 signed to enable the ready setting up of closet jobs where concrete, wood, or tile floors are cast or built around the roughed-in plumbing job.

In such situations it has heretofore been a source of considerable expense to effect the proper placement of the floor flange and closet, where the "closet bend" is in place and the concrete has been cast, or other structure built closely therearound. A temporary stopper has heretofore been employed to close the end of the bend or other pipe terminal in the roughed-in job, but it has usually been necessary to cut out some of the concrete or other floor around the pipe or "bend". It has not been possible to set the floor flange in place on the pipe so 25 that the floor could be formed therearound, because in the pouring and tamping of concrete or other building operations on the floor, and other operations of various construction between the time of placement of the flange and completion 30 of the floor, the flange would become disturbed and knocked askew, and then, being held in the floor it is a most difficult job to get it removed, the concrete, tile, or wood cut away, and the sleeve readjusted as required. Also, cement mor- 35 tar would become engaged in the joint, it having been found impracticable to caulk the joint in advance of finishing the floor when the flange is placed, and cleaning of this material to permit proper caulking would be another expensive and

40 time-consuming job. It is not possible to secure the flange to the pipe and still permit adjustment of the flange to the finally established floor level. With my invention I am enabled to cause the formation of a suitable clearance within the 45 concrete around the waste pipe end, preserve the end of the pipe perfectly clean, and enable easy adjustment and caulking of the floor flange sleeve on the pipe in proper position for reception of the closet thereon in the ideal operative relation 50 desired, without expenditure of work in cutting or cleaning concrete, tile, wood or other material from around or upon any parts of the job, which is an important object of the invention.

Another object of the invention is to enable 55 the protection of the waste pipe opening, and

the formation of the necessary clearance around the pipe terminal with great certainty and in a manner which will enable its accomplishment by unskilled workmen, and at a small cost for materials, time and labor, effecting a considerable saving in the costs of such installations, which is an important attainment, in view of the high cost of plumbing installations now generally involved.

It is a further purpose to provide a novel device for application to the end of a pipe end to attain the ends stated, and others, including the positive support of the device in proper relation to the pipe end so that it will cause a channel to be formed around the pipe end of ample 15 size to accommodate the necessary plumbing connection elements.

Another aim is to present such device which will enable the positive closure of the pipe end in a manner which will not permit of its being 20 opened accidentally and which will not have objectionable projections to interfere with workmen on various jobs in building construction intervening between the roughing in of the plumbing and the final emplacement of the closet fixtures 25 or other fixtures.

It is an important object to enable the ready opening of the applied device involved in my invention with the simplest tools, which will always be available conveniently to the job, for 30 plumbers and others requiring to open the device.

Additional objects, advantages and features of invention reside in the construction, arrangement and combination of parts and the manner of use, as will be understood from the following description and accompanying drawing, wherein

Figure 1 is a longitudinal sectional view of the device.

Figure 2 is a bottom view thereof.

Figure 3 is a sectional view of a typical closet 40 installation incident to new work, at completion of the concrete floor.

Figure 4 is a detail vertical section of the work last shown at installation of the closet.

Figure 5 is a top view of the device in place in 45 the floor, open for installation of the closet.

Figure 6 is a view similar to Fig. 1, showing a modification.

There is illustrated a portion of a building structure 10 of conventional type, typical of a private dwelling bath room closet installation, including joists 11, false floor 12, a waste stack 13 in which a Y, 14 is included to which leads the outlet from a cast bend 15, the inlet to which comprises a terminal plain cast iron pipe section 50 55

- 16 which is extended up through the false floor a suitable distance. A concrete floor 17 of usual aggregates and ordinarily formed with Portland cement is cast over the false floor and upper joist 5 portions of the joists and snugly around the pipe 16, to a distance above the pipe. Set in the concrete and on the pipe, there is a pipe closer and recess form device 18, shown in greater detail in Figures 1 and 4.
- 10 This closer and form consists of a cylindrical receptacle-like body 20, including the circum-scribing wall 21, having a concentrically apertured planiform bottom 22 adapted to receive the pipe 16 therethrough, the bottom adjacent 15 the opening 23 therein constituting a circumscribing continuous horizontal flange. The bottom flange may be formed either integrally with or attached to the wall 21 in a conventional manner according with conventional can manufacturing practice. Fitted on this wall 21 there is a cover 24 consisting of a flat, circular cap plate 25 and a depending circumscribing annular flange 26, fitting frictionally on the wall 21, so that the receptacle and cover are held together securely 20 but manually detachable. The cover with its flange may be formed integrally in one piece from sheet metal, as in can or metal box covers.
- 25 On the inner side of the top plate 25 there is a depending vertical concentric annular wall 27, attached by solder or otherwise, firmly to the top plate 25, although it is not necessary that this joint be water-tight or air-tight. The wall 27 may be tapered so as to fit freely within the pipe 16 as far as necessary to center the wall 27 in 30 the end of the pipe 16, and to extend within the latter a short distance. The height of the wall 27 is somewhat greater than that of the height of the fitting to be accommodated in the floor, such as the sleeve of the floor flange or collar 28 shown in Figure 4, which includes a top horizontal flange 29 slotted at opposite sides to receive 35 closet fastening screws therein when the closet is secured in place, and a depending sleeve portion 30, the interior diameter of which is sufficiently greater than the external diameter of the pipe 16 to afford a space for oakum and lead 40 caulking 31, its lower end being slightly restricted to afford a support for the caulking.
- 45 The body 20 and cover parts may be made of comparatively thin sheet iron, and may be tinned to limit corrosion. The top plate 25, particularly, should be of quite thin material, not thicker than roofing "tin," although it may be much thinner, and may be of a thickness and material corresponding to that in the tops of cans for canning 50 vegetables, preferably soft iron or other metal that may be readily cut as hereinafter described.
- 55 In the use of my invention, the plumbing having been "roughed in", including the pipe 16 60 permanently in place, and the finished surface level of the completed floor having been ascertained, the closer and form device are put in place by adjusting the opening 23 around the pipe and pressing the device downward with the 65 tapered wall 27 entering the pipe 16 until the plate 25 rests on the pipe, the end of which is adjusted at the finished floor level. If necessary the cover 24 may be separated from the body 20 while the parts are put in place and the cover 70 then adjusted snugly on the wall 21, as in Figures 1 and 3. If necessary the plate 25 may be adjusted above the end of the pipe 16 and secured or propped at the proper level. If desired one or more small tongues 32 may be formed integrally on the lower inner edge of the flange 22,

turned down and soldered permanently to the pipe 16, or without such tongues the flange secured by a "tack" of solder to the pipe 16, or other expedient used.

After emplacement of the device as described, 5 the floor 17 may be cast in place around the pipe 16 and the device 18, and tiled flush with the top plate 25, and allowed to become hard set. Other kinds of floors are likewise built snugly around the device abutting closely against the 10 wall 21 or cover. When the closet or other fixture is to be put in place, the plate 25 is cut out with a can opener, or a chisel and hammer, or with a hatchet, or a pocket knife, close to the wall 21, although a portion 33 may be left projecting inward, attached to the flange 26, which is embedded in the concrete and held firmly thereby (see Fig. 4), or as hereinafter indicated, the portion 33 may be connected directly to the wall 21' which corresponds to the wall 21 first 20 described. If desired, the flange 26 may be crimped at its edges to cause it to become locked in the concrete.

If parts 33 are left they may be irregularly shaped, or serrated, notched, or slotted so that 25 the sleeve 30 of the floor flange may be readily pushed downwardly therethrough, and around the pipe 16 a distance. The caulking is then introduced in the familiar way, either by first packing with oakum and then pouring in molten 30 lead, or by caulking lead wool therein in the familiar way, the fitting being unobstructed so that the caulking chisel may be freely applied. The closet 35 may then be set in place and secured to the flange 29 by the usual bolts and nuts. 35 Usually the finished concrete floor includes a tiled surface portion 36 applied over the cast concrete 17, and this tiling may also abut the wall 21 and plate 25, so as to underlie the flange 29. Linoleum or rubber sheet flooring also is 40 fitted closely around the wall 21 of the device when such flooring is installed.

The top plate 25 may be joined permanently and directly to the wall 21, as at 25' and 21' in Fig. 6, so that the whole device is an integral 45 unit except as found necessary to join the parts by seams or other permanent connections. The last mentioned form of the device may be put in place in the same manner as already described, in one operation, the reduced end of the wall 50 27' readily entering the pipe 16 after the latter has been projected through the opening 23' in the bottom flange 22'. The top wall 25' and bottom flange 22' may be attached to the wall 21' by any conventional seam, as at 34, if desired. The parts in Figure 6 corresponding to those first described have the same reference characters with the addition of a prime mark.

It will be understood that the embodiment 60 presented is purely exemplary, although it is the best form in which the invention has thus far been embodied, but it may be modified in various ways without departing from the spirit of the invention as set forth in the appended claims.

Thus, to make more secure the hold of the cover 24 on the body 20, any special joints or connections other than the simple friction sleeve flange 26 may be employed; and the proportions of the device varied to adapt it to use on larger or smaller jointings or mountings of articles in concrete and other structures in such situations as illustrated and various others, the invention not being limited to water connections or joints specifically.

It will be understood that the term "severable" as used in the claims will include frangible material, meltable material or tearable ones.

I claim:

- 6 1. A pipe closer and recess former for concrete structures, consisting of a body member having an annular wall constructed to lie around a pipe in spaced relation thereto and having a bottom flange projected inwardly therefrom to lie close to and circumscribe such pipe, a top plate member thereon constituting a closure for the device and an inner annular wall depending therefrom to lie within an engaged pipe, said top plate member being of thin sheet metal 5 adapted to be easily cut with common edged tools.
- 10 2. A pipe closer and recess former for concrete structures, consisting of a cylindrical wall element having at its bottom part an integral inwardly projected perimetral flange to receive pipe therethrough, and a top plate thereover forming a closure undetachably connected to the wall when in place in the finished concrete, but being of thin sheet metal adapted to be easily 15 cut by edged tools.
- 15 3. The structure of claim 2 in which said top plate consists of a circular thin sheet metal plate having a circumferential cylindrical flange shaped and sized to fit frictionally and manually 20 removable upon the upper edge portion of the said wall.
- 25 4. A pipe closer and recess former for concrete 25

structures and the like, consisting of a case wall element having at its bottom an integral inwardly projecting flange to receive a pipe therethrough, and a top plate fixed thereon when in place in the concrete consisting of a severable 5 removable material.

5. A pipe closer and mounting former for fixtures and the like in building structures, consisting of a case element having at its bottom an anchoring means, and adapted to be built into 10 the building structure adjacent a surface thereof and having a top wall removable by severance substantially as described.

6. A pipe closer and mounting former for fixtures and the like in building structures, consisting of a case element having at its bottom a mounting means constructed for engagement on a fixed member in the building, said case being adapted to be permanently built rigidly into 15 the building structure adjacent a surface thereof, 20 and having an integrally joined sealing but severable top wall.

7. The structure of claim 4, said top plate being provided with a depending pipe-centering member spaced inwardly from said case wall element, a portion thereof intermediately of the height of the case wall element being nearer the longitudinal axis of the device than the inner edge of said flange whereby to engage an upper portion of a pipe inserted in the device, and 30 center the same.

FRED GERRIETS.
